CLAIM

The ornamental design for a food package, as shown and described.

DESCRIPTION

FIG. 1 is a front elevational view of a food package showing our new design; the rear elevational view being a mirror image thereof;

FIG. 2 is a top plan view thereof;

FIG. 3 is a bottom plan view thereof;

FIG. 4 is a right side elevational view thereof; the left side elevational view being a mirror image thereof;

FIG. 5 is a top plan view thereof shown in an open position for clarity of illustration;

FIG. 6 is a front elevational view of a second embodiment of FIG. 1; the rear elevational view being a mirror image thereof;

FIG. 7 is a top plan view of FIG. 6;

FIG. 8 is a bottom plan view of FIG. 6;

FIG. 9 is a right side elevational view of FIG. 6; the left side elevational view being a mirror image thereof;

FIG. 10 is a top plan view of FIG. 6 shown in an open position for clarity of illustration;

FIG. 11 is a front elevational view of a third embodiment of FIG. 1; the rear elevational view being a mirror image thereof;

FIG. 12 is a top plan view of FIG. 11;

FIG. 13 is a bottom plan view of FIG. 11;

The right side of FIG. 11 is identical to FIG. 4 and the left side of FIG. 11 is a mirror image thereof;

FIG. 14 is a top plan view of FIG. 11 shown in an open position for clarity of illustration;

FIG. 15 is a front elevational view of a fourth embodiment of FIG. 1; the rear elevational view being a mirror image thereof;

FIG. 16 is a top plan view of FIG. 15;

FIG. 17 is a bottom plan view of FIG. 15;

The right side elevational view of FIG. 15 is identical to FIG. 4 and the left side elevational view is a mirror image thereof; and,

FIG. 18 is a top plan view of FIG. 15 shown in an open position for clarity of illustration.
